COMPRESSOR UNLOADER MECHANISM

Wade H. Wineman, Michigan City, Ind., assignor
to Joy Manufacturing Company, a corporation
of Pennsylvania

Application December 30, 1943, Serial No. 516,139

12 Claims. (Cl. 230—31)

1

My invention relates to controlling apparatus for pumps, and more particularly to pressure responsive means for controlling automatically the unloading and loading of a pump, such as an air compressor, to maintain its discharge pressure within desired limits.

It is desirable in certain pumping systems that means extremely sensitive to variations in pressure be provided for controlling automatically the discharge of fluid from the systems. By providing means which responds to slight changes in pressures at which fluid is discharged from the pumping system and causing such means, as it responds to the pressure changes, to produce an amplified force for effecting actuation of control devices such as step unloading means, a very sensitive control of the system is obtained. Preferably, in a compressor control system, I utilize selenium relays, i. e., instruments wherein a beam of light, deflected variably by a member moving in accordance with changes in compressor discharge pressure, is caused to sweep across a plurality of selenium cells for producing electrical currents which actuate means controlling the flow of operating fluid relative to suitable compressor unloading means. It is not desired that the production of electrical currents for such control systems be limited to selenium cells, for it is known that other substances than selenium are affected as to electrical qualities by the variation of illumination. It is also not desired to limit the invention to the use of light as the radiant energy employed since thermo couples may be used in place of selenium cells, in which case heat rays take the place of light rays, and these rays may be reflected in the same manner as light rays.

It is an object of my invention to provide improved means for controlling the operation of a pumping mechanism. Another object is to provide an improved control system for pump unloading means. Still another object is to provide in an improved control system for pump unloading mechanism, means responsive to radiant energy for effecting actuation of said unloading mechanism, and means responsive to the pump discharge pressure for transmitting radiant energy to said first mentioned means. Yet another object of my invention is to provide for a pump unloading mechanism an improved control system comprising selenium cells for supplying electrical energy to effect actuation of said unloading mechanism, and means responsive to the pump discharge pressure for directing a light beam on said selenium cells. Still another object is to provide an extremely sensitive unloading control system for a pump mechanism. Another object is to provide improved compressor controlling apparatus which is responsive to radiant energy.

2

Other objects and advantages of the invention will hereinafter more fully appear.

In the accompanying drawings there are shown for purposes of illustration a preferred form and a modification thereof which the invention may assume in practice.

In these drawings:

Fig. 1 is a diagrammatic view of a compound compressor having the preferred form of my control means associated therewith, parts of the control means being shown in section to facilitate illustration.

Fig. 2 is a side elevational view of a portion of the compressor control means shown in Fig. 1.

Fig. 3 is an enlarged vertical sectional view showing one of the unloading devices installed in the ends of the compressor cylinders.

Fig. 4 is an enlarged view of a portion of the control means with parts shown in section, the view being taken on the planes of the line 4—4 of Fig. 1.

Fig. 5 is a sectional view taken on the line 5—5 of Fig. 4.

Fig. 6 is a view taken in the plane of Fig. 1 and showing a modification of the control means.

To illustrate the invention there is shown a compound compressor, generally designated 1, having the improved control means associated therewith and generally designated 2. It will be evident, however, that the control means may be utilized with compressors of various types, or with other mechanisms as well, and that the compressor shown herein is merely illustrative of one of the types of compressors with which the control means is adapted for use.

The compressor comprises a base 4 having a pair of low pressure cylinders 5, 5' and a pair of high pressure cylinders 6, 6' projecting radially therefrom. Reciprocable within the low and high pressure cylinders are pistons, not shown, connected through suitable means to a crankshaft 7 journaled within the base 4 and driven by any suitable power means, not shown. Air is supplied through connections 8, 8' to the low pressure cylinders 5, 5', where it is compressed and discharged through intercoolers 9, 9' and connections 10, 10' to the high pressure cylinders 6, 6' where it is compressed again and whence it is discharged to connections 11, 11' leading to a storage tank, not shown, or to a point of use. The compressor cylinders shown are adapted for the compression of air on each stroke of their respective pistons, and arranged within cylinder heads 12 at both ends of the cylinders are unloading devices, generally designated 13.

The inlet valve devices 14, or at least one at each end of each cylinder, has, as shown in Fig. 3, a follower member 15 which is received within a chamber 16 in the cylinder head and engages an inlet valve mechanism proper, gen-

2,420,159

3

erally designated 17, for holding the latter in place within an opening 18 connecting the chamber 16 in communication with a clearance space 19 at the end of the cylinder bore. Air is conducted to the chamber 16 through an inlet passage 20, and inlet valves 21 control the flow of air from the chamber 16 to the clearance space 19 and the cylinder bore. Attached to the outer end of the member 15, as by screws 23, is a cap 24 having a recessed inner surface which cooperates with a recessed end surface on the member 15 to form a chamber 25. A diaphragm 26 is clamped in the chamber 25 between the cap 24 and the member 15, and attached to the diaphragm is a rod 27 extending through an opening in the member 15 and carrying at its inner end a member having fingers 28 which are adapted to engage the inlet valves to unseat the latter and effect unloading. A suitable outer cover element 30 is secured, as by screws 31, to the cylinder head above the chamber 16, and a tubular clamping screw 32 is threaded through an opening in the cover element into engagement with the cap 24 for holding the member 15 in clamping engagement with the valve mechanism 17. Threaded on the outer end of the clamping screw is a guard cap 33 having an opening 34 through which pressure fluid may pass. Formed in the cap 24 in axial alignment with the screw 32 is a passage 35 opening into the chamber 25. When pressure fluid is supplied through the opening 34, the tubular screw 32 and the passage 35 to the chamber 25, the diaphragm 26 is forced inwardly and moves the fingers 28 into engagement with the inlet valves for unseating the latter. When pressure fluid is vented from the chamber 25, the diaphragm 26 is forced outwardly by a spring 36 for moving the fingers out of engagement with the valves.

Valve devices, generally designated 37, 38, 39 and 40, are provided for controlling the flow of pressure fluid relative to the various unloading devices. Each of these valve devices comprises, as shown in Figs. 4 and 5, a valve casing 41 having a central chamber 42 communicable through valve bushings 43 with end chambers 44 and 45. Arranged in the chambers 44 and 45 are valve members 46 and 46' urged by springs 47 toward seats on the valve bushings for controlling the flow of pressure fluid between these chambers and the central chamber. The valve members 46 and 46' are provided with guide-ribbed portions 48 projecting through the valve bushings into the central chamber to engage opposite sides of a lever 49 which is pivotally connected at one end to the valve casing and is connected at its other end to a plunger 50 extending into a coil of an electromagnet 51. Pressure fluid is supplied to the chambers 45 from a supply line 53 through branch connections 54. The chambers 44 are connected to atmosphere through vent ports 55. The central chamber of the valve device 37 is connected by a conduit 56 and branch conduits 57 and 58 to the unloading devices in the head ends of the low pressure cylinder 5 and the high pressure cylinder 6. A conduit 59 connects the central chamber of the valve device 38 to branch conduits 60 and 61 leading to the unloading devices in the head ends of the low pressure cylinder 5' and the high pressure cylinder 6'. The unloading devices in the crank ends of the low pressure cylinder 5 and the high pressure cylinder 6 are connected by conduits 62 and 63 to a conduit 64 leading to the central chamber of the unloading device 39. A conduit 65 con-

nects the central chamber of the valve device 40 to branch conduits 66 and 67 leading to the unloading devices in the crank ends of the low pressure cylinder 5' and the high pressure cylinder 6'. It will be seen that on energizing the coils of the electromagnets, the levers 49 are swung upwardly about their pivots and force the valves 46' from their seats so that pressure fluid is supplied from the chambers 45 to the central chambers 42 where it enters the conduits 56, 59, 64, 65 and is conducted to the unloading devices for unloading the compressor cylinders. When the coils of the electromagnets are de-energized, the plungers 50 drop and swing the levers 49 about their pivots to open the valves 46 for venting pressure fluid from the unloading devices through the vent ports 55 in the lower chambers 44.

The energizing and de-energizing of the electromagnets are controlled by the improved control means 2. This control means, as illustrated, comprises a reflector 70 for deflecting a light beam 71 so that it is directed against light sensitive devices such as selenium cells 72, 73, 74 and 75. The reflector 70 is movably supported so that the deflected light beam may be caused to sweep across the cells and is shown herein as being fixed in any suitable manner to a plate 77 which is pivotally mounted at 78 on a member 79. Formed in the member 79 is a recess 80 cooperating with a recess in a cover plate 81 to provide a diaphragm chamber 82 within which a diaphragm 83 is clamped. Fixed to the diaphragm are circular discs 85 carrying a rod 86 which fits loosely within an opening in a plug 87 and is adapted to be engaged at its outer end by a pointed projection 88 fixed to the plate 77. Surrounding the rod 86 is a coiled spring 89 acting between the plug 87 and the discs 85 to urge the rod 86 in a direction away from the projection 88. Fluid at compressor discharge pressure is supplied through a conduit 80 to the diaphragm chamber 82 where it acts against the diaphragm and tends to move the latter against the force of the spring 89. A shoulder 91 on the member 79 is engageable by the plate 85 for limiting movement of the rod 86 by compressor discharge pressure. Acting between the plate 77 and the member 79 at the side of the pivot mounting 78 opposite from the projection 88 is a spring 92 which tends to swing the plate about its pivot and hold the projection 88 firmly against the end of the rod 86.

A source of light is provided within a casing 93 supported in any suitable manner above the selenium cells, herein an electric light bulb 94, and light from the bulb shines through a lens 95 onto the reflector 70. The light may of course be located at any point from which its beam may be deflected to the cells or, if desired, a suitable mounting may be provided for the light in the place of the reflector 70 so that the light shines directly onto the selenium cells and is moved across the cells as the discharge pressure changes. The beam of light directed toward the selenium cells must be fanned out or expanded angularly in a plane which intersects each of the cells so that all the cells may be illuminated at the same time when the compressor discharge pressure has reached the maximum desired value and it is necessary to unload the compressor completely.

Connected across the selenium cells 72, 73, 74 and 75 are electrical circuits including electromagnets 96, 97, 98 and 99 which are adapted,

when energized, to move contactors 100, 101, 102 and 103 into engagement with contacts 105, 106, 107 and 108. The contactors 100, 101, 102 and 103 are connected, respectively, through electromagnets 110, 111, 112 and 113 to a conductor 114 leading to a power line L₁, and the contacts 105, 106, 107 and 108 are connected to a conductor 115 leading to a power line L₂. The electromagnets 110, 111, 112 and 113 are adapted, when energized, to move contactors 117, 118, 119 and 120 into engagement with contacts 121, 122, 123 and 124. The contacts 121, 122, 123 and 124 are each connected to the power line L₂, and the contactors 117, 118, 119 and 120 are connected, respectively, by conductors 126, 127, 128 and 129 to one end of the coils of the electromagnets for the valve devices 37, 38, 39 and 40. The other end of the coils for the valve devices are connected to the power line L₁. It will be understood that two sets of electromagnetically controlled switches have been used between the selenium cells and the valve devices only because the currents produced by the cells are not strong enough to actuate contactors capable of carrying currents for actuating the valve devices. For other types of devices controlling the flow of operating fluid relative to compressor unloading means, an amplification of the currents produced by the cells may not be necessary.

The mode of operation of the mechanism described is as follows: Assuming that the compressor discharge pressure is low and that the diaphragm 83 is held by the spring 89 in a position such that the light beam deflected from the reflector 70 passes above the selenium cell 72 as viewed in Fig. 1, then the coils for the valve devices 37, 38, 39 and 40 will be de-energized and the plungers 50 will move the valves 46 into positions venting fluid from the unloading mechanisms 18 through the exhaust ports 55, and the compressor will operate fully loaded. As the compressor discharge pressure increases, the diaphragm 83 is forced in a direction to swing the plate 77 about its pivot 78 against the force of the spring 92. The reflector 70 swings with the plate 77 and causes the light beam to move angularly toward the selenium cells. As the light beam strikes the selenium cell 72, an electric current is caused to flow through the electromagnet 86 for moving the contactor 100 into engagement with the contact 105. Current then flows from the line L₁ of the power line through the conductor 114, the electromagnet 110, the contactor 100, the contact 105 and the conductor 115 to the other line L₂ of the power line. Current flowing through the electromagnet 110 causes the contactor 117 to be moved into engagement with the contact 121 and current then flows through the power line L₂, the coil of the valve device 37, the conductor 126, the contactor 117 and the contact 121 to the power line L₂. With the energizing of the coil of the valve device 37, the plunger 50 is raised and swings the arm 49 about its pivot opening the valve 46' and permitting the valve 46 to be seated by the spring 47. Fluid then flows from the supply conduit 53 through the branch conduit 54 to the chamber 45 where it passes the valve 46' to the central chamber 42 and is conducted by the conduit 56 and the branch conduits 57 and 58 to the unloading devices 13 in the head ends of the low and high pressure cylinders 5 and 6 for effecting an unloading of these cylinder ends. If the discharge pressure continues to increase, the diaphragm 83 will be forced inwardly by the discharge pres-

sure and swing the reflector 70 until the light beam strikes the selenium cell 73 as well as the cell 72. Electric currents produced by the cells 72 and 73 will cause electrical circuits to be established for operating the valve devices 37 and 38 to supply operating fluid to the unloading devices in the head ends of the low pressure cylinders 5, 5' and the high pressure cylinders 6, 6', thereby effecting an unloading of these ends. On further increase in discharge pressure, the reflector 70 is moved to a position so that the light beam is directed upon the cells 72, 73 and 74. Current produced by the cell 74 causes circuits to be established for operating the valve device 39 and supplying fluid to the unloading devices in the crank ends of the low and high pressure cylinders 5 and 6. At a maximum discharge pressure, the reflected light beam is moved to a position illuminating the cells 72, 73, 74 and 75. At this time all the valve devices 37, 38, 39 and 40 will be operated to effect an unloading of the head and crank ends of each of the compressor cylinders.

In the modification of the invention shown in Fig. 6, the reflector 70 is attached to a Bourdon tube 130 to which compressor discharge pressure is supplied through the conduit 90. The Bourdon tube 130 responds to variations in the compressor discharge pressure to move the reflector 70 for swinging the light beam across the selenium cells 72, 73, 74 and 75. Currents flowing through the selenium cells, when the light beam is directed upon them, establish circuits for operating the valve devices 37, 38, 39 and 40 to effect a step control of the compressor unloading devices in the same manner as described in the preferred form of the invention.

As a result of this invention there is produced an extremely sensitive control system for a pump mechanism. It will be noted that the degree of sensitivity of the system may easily be adjusted by varying the distance between the reflector and the selenium cells or by changing the position of the plug 87 so as to vary the opposition offered by the spring 89 to movements of the diaphragm 83. Advantages of the system will be clearly apparent to those skilled in the art.

While I have in this application specifically described one form and a modification thereof which my invention may assume in practice, it will be understood that this form and modification of the same are shown for purposes of illustration and that the invention may be further modified and embodied in various other forms without departing from its spirit or the scope of the appended claims.

What I claim as new and desire to secure by Letters Patent is:

1. In a pumping mechanism, in combination, a pump, driving means for said pump, fluid actuated unloading means for said pump for effecting unloading while drive continues, means for controlling the flow of operating fluid relative to said unloading means including an element responsive to radiant energy, means for producing a beam of radiant energy, and means controlled by the discharge pressure of said pump for directing said beam of radiant energy upon said element when the discharge pressure reaches a predetermined maximum value.

2. In a pumping mechanism, in combination, a pump, driving means for said pump, fluid actuated unloading means for said pump for effecting unloading while drive continues, means for controlling the flow of operating fluid relative to said

unloading means including an element responsive to radiant energy, means for producing a beam of radiant energy, and means responsive to pump discharge pressures for effecting a striking of said beam upon said element when a predetermined discharge pressure is reached.

3. In a pumping mechanism, in combination, a pump, driving means for said pump, fluid actuated unloading means for said pump operative to perform its unloading function while pump drive continues, means for controlling the flow of operating fluid relative to said unloading means including an element responsive to light rays, means for producing rays of light, and means responsive to pump discharge pressure for directing said rays of light on said element when a predetermined maximum discharge pressure is reached.

4. In a pumping mechanism, in combination, a pump, fluid actuated unloading means for said pump, means for controlling the flow of operating fluid relative to said unloading means including an element responsive to light rays, means for producing rays of light, means for deflecting said rays of light into a plane including said element, and means responsive to pump discharge pressure for actuating said deflecting means to direct said deflected rays of light upon said element.

5. In a compressor mechanism, in combination, a compressor, driving means for said compressor, fluid actuated unloading means operative to effect a step unloading of said compressor while drive of the latter is continued, means for controlling the flow of operating fluid relative to said unloading means including a plurality of elements responsive to radiant energy, means for producing a beam of radiant energy, and means responsive to compressor discharge pressure for directing said beam of radiant energy cumulatively upon said elements as the discharge pressure increases so that one element, or a plurality of elements including said one element, shall be subjected to said beam.

6. In a compressor mechanism, in combination, a compressor, fluid actuated unloading means operative to effect a step unloading of said compressor, means for controlling the flow of operating fluid relative to said unloading means including a plurality of selenium cells, means for producing rays of light, and means responsive to compressor discharge pressure for effecting an interruption of said light rays by said selenium cells.

7. In a compressor mechanism, in combination, a compressor, fluid actuated unloading means operative to effect a step unloading of said compressor, means for controlling the flow of operating fluid relative to said unloading means including a plurality of selenium cells arranged in a common plane, means for producing a beam of light, means for deflecting said beam of light into the plane including said selenium cells and expanding the beam angularly within said plane to a width including all of said cells, and means responsive to compressor discharge pressure for actuating said deflecting means to direct said light beam upon said cells.

8. In a compressor mechanism, in combination, a compressor, fluid actuated unloading means operative to effect a step unloading of said compressor, means for controlling the flow of operating fluid relative to said unloading means including a plurality of selenium cells arranged in a common plane, means for producing a beam of light, means for deflecting said beam of light into the plane including said selenium cells and expanding the beam angularly within said plane to a width

including all of said cells, and means responsive to compressor discharge pressure and operating as the discharge pressure increases to actuate said deflecting means and direct the light beam cumulatively upon said cells.

9. In a pump mechanism, in combination, a pump, fluid actuated unloading means operative to effect a step unloading of said pump, means for controlling the flow of operating fluid relative to said unloading means including a plurality of elements responsive to radiant energy and arranged side by side in a common plane, means for directing a beam of radiant energy in said plane of sufficient width to include all of said elements, and means responsive to pump discharge pressure and operating with increases in pressure to actuate said directing means in a direction to move said beam cumulatively upon said elements.

10. In a pump mechanism, in combination, a pump, driving means for said pump, unloading means for said pump for reducing the work done by the latter while said driving means continues to drive the same, means for controlling said unloading means including an element responsive to radiant energy, means for producing a beam of radiant energy which is adapted to be intercepted by said element, and means responsive to pump discharge pressure for effecting an interception of said beam by said element when a predetermined discharge pressure is reached.

11. In a pump mechanism, in combination, a pump, driving means for said pump, unloading means operative to effect a step unloading of said pump while drive thereof by said driving means continues, means for controlling said unloading means including a plurality of elements responsive to radiant energy each controlling one step of unloading, means for producing a beam of radiant energy which is adapted to be directed cumulatively upon said elements to effect step unloading progressively, and means responsive to pump discharge pressure for directing said beam cumulatively upon said elements as predetermined pressure changes take place.

12. In a pump mechanism, a pump, driving means for said pump, means for effecting step unloading of said pump to effect unloading thereof to different degrees while drive thereof by said driving means continues, said means for effecting step unloading having for each step a radiant energy responsive control element, the control elements for the several steps of unloading arranged within a predetermined area, a source of radiant energy, and means for subjecting said control elements to energy from said source successively and cumulatively in a predetermined order as compressor discharge pressure increases and for interrupting such subjecting in reverse order as compressor discharge pressure decreases.
